R. G. TALLEY ET AL

RING LATCH

Filed Sept. 1, 1923

Inventor
R. G. Talley & W.W. Talley

By *A. Murphy Jr.* Attorney

UNITED STATES PATENT OFFICE.

ROBERT G. TALLEY AND WALDEMAR W. TALLEY, OF CALIFORNIA, MISSOURI.

RING LATCH.

Application filed September 1, 1923. Serial No. 660,581.

This invention relates to latches for doors, gates and other closures, and has for an object the provision of a latch for the purpose indicated which shall employ a locking ring 5 to be engaged by a lug carried by a gate or other closure to which the invention is applied, and which locking ring is so suspended that it will be moved by the lug to permit the device passing under it when the 10 gate is moving to closed position, but which will quickly return to normal position to prevent the gate rebounding into an open position no matter with what force the gate is swung closed.

15 Another object of the invention is to provide means for adjustably securing the latch in place on a gate post or the like, whereby it may be adjusted toward the gate when the gate posts spread.

20 A further object of the invention is to provide a supporting frame for the latch ring which shall be provided with a slot in which the ring operates and which slot shall be in the form of an arc so that the ring 25 will be in a position to be squarely engaged by the gate carried locking lug.

Another object of this invention is to provide a latch which is simple, durable and efficient, and which may be manufactured 30 and sold at a comparatively low cost, and which may be readily and easily installed by an unskilled workman.

With the foregoing and other objects in view, as will become more apparent as the 35 description proceeds, the invention consists in certain novel features of construction, combination and arrangement of parts as will be hereinafter more fully described and claimed.

40 In the accompanying drawings:

Figure 1 is a view in elevation showing a gate provided with a latch constructed in accordance with my invention, and secured in closed position.

45 Figure 2 is a top plan view of the same, Figure 3 is a front elevation showing the gate carried latch lug in section,

Figure 4 is a perspective view of the latch, the rings being omitted.

50 Referring in detail to the drawings, the numeral 5 indicates a gate hingedly mounted for swinging movement and supported by the gate post 6. There is also provided a latch supporting gate post 7. These posts 55 are of well known construction, and are

shown merely for the purpose of illustrating the application of my invention.

Secured to the gate post 7 by means of a relatively long and heavy screw 8, is the latch ring supporting frame 9 comprising 60 the spaced side bars 10 having their ends closed as indicated at 11. The bars 10 are longitudinally curved as shown and have substantially the same degree of curvature as the line described by the free end of the 65 gate 5 when the gate is swung on its pivot.

These bars 10 are provided adjacent their closed ends and near their lower edges with registering openings 12 through which are passed bolts 13. Loosely mounted on the 70 bolts 13 are relatively large rings 14 each of which has a radius equal to a distance greater than the distance between the bolts 13 and the adjacent closed ends 11 of the ring supporting frame 9.

In attaching the latch to the gate post 7, it is necessary to employ a boring tool to make an opening in the post and the screw 8 may be turned into the opening by using the frame 9 for a hand grip and to obtain a 80 leverage. One of the spaced side bars 10 is provided with an upstanding ear 15 through which a screw or like fastening 16 may be passed to assist the screw 8 in securing the latch 9 to the post 7 and to prevent the lug supporting frame 9 from rotating with the screw 8 as a pivot. The screw 8 is located 85 centrally between the ends and the upper and lower edges of that side of the frame 9 to which it is secured, and the ear 15 is located within the plane of said side and centrally between the ends thereof. When the posts 6 and 7 spread, the latch ring supporting frame 9 may be adjusted toward the gate 90

5 by giving the latch ring supporting frame a few turns, and after this shall have been done the fastening element is passed through the ear 15 into the post 7 so as to hold the frame 9 against casual movement.

In the practical operation of the device, 100 the gate is provided with a locking lug 17 which when the gate is swung to close the same, moves one of the latching rings 14 in an upward direction and passes beneath the same. When the lug 17 moves to a position at the inner side of the ring engaging it, it is necessary to grasp the ring and elevate the same in order to open the gate, as the harder the lug presses against the inner side of the ring the harder the ring binds against its 105 110

supporting bolt 13 and the adjacent closed end 11 of the frame.

The lower outer edges of the latch ring supporting frame 9, are beveled as indicated at 18, so as not to interfere with the movement of the lug 17. As the frame 9 is curved longitudinally and secured in place with its concave side next to the free end of the gate 5, the rings 14 are supported in such position with respect to the path described by the lug 17 during the closing of the gate 5, that comparatively little force is required to permit the lug 17 to lift the ring 14 with which it contacts during the closing of the gate 5. Owing thereto, the gate 5 will be latched in closed position no matter how little force is employed in swinging it into closed position. As the rings 14 are supported from points near the lower edges of the ends 11 of the frame 9, the actuated ring will quickly return to its normal position, and in view thereof the gate will be latched when violently swung into closed position.

While we have shown and described the preferred embodiment of our invention, it will be understood that minor changes in construction, combination and arrangement of parts may be resorted to without departing from the spirit or scope of the invention as claimed.

Having thus described our invention, what we claim is:

A latch of the character set forth, comprising a frame, an attaching screw fixed at one end to one side of the frame and located centrally between the ends and the upper and lower edges of said side, an upstanding ear formed integrally with the upper edge of said side and located in the plane of said side and centrally between the ends thereof, and rings supported within the frame.

In testimony whereof we affix our signatures.

ROBERT G. TALLEY.
WALDEMAR W. TALLEY.
